ENGINE STARTING APPARATUS

Joseph W. Allen, East Orange, N. J., assignor to
 Eclipse Aviation Corporation, East Orange,
 N. J., a corporation of New Jersey

Application June 18, 1935, Serial No. 27,270

2 Claims. (Cl. 74—7)

This invention relates to engine starting apparatus and more particularly to power means for cranking internal combustion engines.

One of the objects of the invention is to provide a novel electric started that is symmetrical in form, and embodying means for rotating the engine engaging member at a much lower speed than that of the armature shaft of the motor.

Another object is to provide means for rotating the engine engaging member through the instrumentality of a shaft extending through the armature shaft of the motor.

These and other objects and advantages to be derived from the use of the invention herein disclosed will become evident from an inspection of the following description when read with reference to the accompanying drawing illustrating one embodiment of the invention. It is to be expressly understood that the illustrated embodiment is not exclusive, and various other embodiments will now suggest themselves to those skilled in the art, while changes may be made in the construction, arrangement and proportions of parts, and certain features used without other features, without departing from the spirit of the invention. Reference is therefore to be had to the claims hereto appended for a definition of the limits of the invention.

In the drawing, reference characters 3, 4 and 5 designate the three sections of the enclosing housing, the sections having suitable flanges to receive bolts 6 for detachably connecting said sections. The inner section 3 is provided with a flange 1 to receive bolts 8 for securing the starter to the crankcase of an engine, a portion of the latter being indicated at 9. Secured to the central section 4 is an electric motor provided with an armature 10 and pole shoes 11 to receive screws 12 which may be employed for detachably securing the motor to the housing 4.

The motor may be of any suitable type embodying an armature shaft 13 provided with a laterally projecting, reduced portion 14 that is rotatably mounted as by means of a suitable bearing 15 in a transverse wall of housing section 4.

Gear 25 constitutes a sun gear for a plurality of planetary gears 31 that are rotatably mounted on a plate 29 and mesh with an internal gear 32 which is fixedly mounted within the housing by means of screws 33. Preferably three planetary gears 31 are employed, spaced 120° apart, so that as the view is taken in Fig. 1, one of the gears appears in elevation just below the sun gear 25, and one in section above said sun gear.

Each of the planetary gears is rotatably mounted by means of a ball bearing 34 carried by a sleeve 35 which is countersunk at its inner end in barrel end 29. Extending through sleeve 35 and threaded into the barrel end 29 is a screw 36 which supports the sleeve, bearing and planetary gear. If desired a retaining ring 37 for bearings 34 may be formed integral with sleeves 35.

The plate 29 is adapted to drive an engine engaging member 38 and is in turn driven through the agency of the planetary reduction gearing described above. The member 38 constitutes one element of a jaw clutch, the other element being formed by a member 39 carried by a rotating part of the engine to be cranked, such as the engine crankshaft or an extension thereof.

Normally members 38 and 39 are disengaged, the member 38 being adapted for longitudinal movement into driving engagement with member 39, preferably by spring means 46 and automatic screw means 44 having splined engagement with hub 45 of clutch 38, and similar to that disclosed in Lansing Patent No. 1,962,397, granted June 12, 1934. In order that the parts of the apparatus and particularly the reduction gearing may be made as light as possible, it is desirable to provide yielding means intermediate the train of gearing described above and the engine engaging member 38, whereby the energy stored in the motor armature is ineffective to damage said gearing when the clutch member 38 suddenly engages the stationary engine member 39. For this purpose there is preferably employed a multiple disk clutch embodying a plurality of friction disks 40 held engaged by pre-set springs 42, a number of said disks being splined to the inner surface of a barrel 28 integral with plate 29, and the remainder being splined to the outer surface of an interiorly threaded nut 41, corresponding to the nut 41 of the Lansing Patent No. 1,962,397.

As in the said Lansing patent, the starter is preferably provided with oil sealing means for preventing oil in the engine crankcase 9 from seeping into the starter housing. For this purpose there is fitted over the inner end of the starter a cup-shaped member 48 that is preferably formed of metal and is provided with a flange 49 on the outer end thereof, said flange being adapted to be clamped between flange 7 of the starter housing and the engine crankcase. The automatic meshing is facilitated by provision of a circular resilient member, such as a coil spring 58 which rests in an annular groove formed in the outer periphery of a ring 57, and 55

is adapted to rotate on the curved lip surrounding the central opening in member 48, in the manner described more fully in the Lansing Patent No. 1,962,397.

5 As illustrated the planetary gear assembly 31 is adapted to receive rotation from either of two sources, namely, motor 10 or a manually operable shaft 26; and in each case the driving connections to the said gear train include a connecting shaft 10 61 passing centrally through the armature shaft 13 but with sufficient clearance to be readily rotatable relatively thereto, and terminating in the plane of the barrel end 29 to which it imparts rotation by reason of the positive connection to 15 the planetary gear set constituted by suitable key means 63 drivably engaging a longitudinally extending groove or key-way formed along the inner surface of the sun gear 25. The opposite end of the shaft 61 is also grooved or splined to receive 20 the correspondingly splined hub 64 of a bevel gear 65 adapted to mesh with the bevel pinion 66 formed on the end of a shaft 67 having a positive connection 68 with the manually operable shaft or sleeve 26 heretofore referred.

25 The gear 65, by reason of the connections above described, operates to drivably connect the manually operable shaft 26 with the planetary gear set 31. There will now be described the means whereby this same gear 65 operates to drivably 30 connect the armature shaft 13 with the driven gear set 31. As shown such means includes two additional planetary gear combinations 71 and 72, the planet members of which revolve about a common internally toothed annular track or orbit 35 73 held fast within the casing section 5 by suitable means including a flange portion 74 secured within a recess between the abutting flanges of the casing sections 4 and 5. The planet members 72 rotate about their mounting pins 70 secured to the gear 65 through the instrumentality of retainer sleeves 71 with which the mounting pins 70 threadedly engage, while the planet members 71 rotate about mounting pins 78 which are similarly secured to the periphery 79 of a 40 mounting gage or spider 80 having a hub 81 provided with teeth constituting a sun gear 82 with which the planet members 72 are maintained in constant mesh. A similar sun gear 85 meshes with the planets 71 and is internally splined or 45 grooved to engage corresponding splines 86 formed along the outer surface of the reduced portion 14 of the armature shaft 13, the gear 85 being held in position of abutment with the inner race of bearing 15 by suitable retaining means 50 87. A similar retaining nut 88 adjustably holds the commutator and armature 18 against longitudinal displacement in one direction while the shoulder or flange 90 on armature shaft 13 performs a similar function by preventing displacement 55 in the opposite direction as well as serving in conjunction with ring 91 as a retaining means for the bearing 92, the outer race of which is constituted by a hub 93 formed on the end plate 94 which encloses the yoke 96 which receives 60 the field coils 97 of the motor.

In order to prevent reverse rotation of either the manually or electrically operating driving elements such as might occur in the event of a backfire or premature ignition in the cylinders of the engine during cranking, means are provided 5 between the hub 64 of gear 65 and an annular extension 101 secured to the inner surface of the end section 102 of the casing 5. As shown, such means includes a plurality of rollers 105 mounted in depressions formed in the periphery of an annular ring 103 corresponding to the inner race of a conventional overrunning clutch and adapted to roll freely in said depressions while the gear 35 is rotating in one direction but capable of being wedged against the surface of the ring 101 upon reverse rotation of the gear 65 whereupon said ring 101 and the rollers 105 act as a positive stop to prevent any appreciable movement of said gear 65 or the parts connected thereto in such reverse direction. The rollers 105 are held in 10 20 position by suitable retainer rings 107 and 108, the latter being in turn retained on the reduced end of shaft 61 by the provision of the retaining nut 111 which also serves, in conjunction with the retainer cup 112 to hold the bearing 113 in 25 position.

In order to provide a completely shielded construction the motor cable 115 is preferably sheathed in metal and terminates in a connection 116 protected by a metallic shield 117 30 grounded to the casing as indicated in 118, and the brush retainers 119 are likewise shielded by the provision of metallic covers 120. Preferably these brush retainers 119 are of a construction 35 such as is disclosed and claimed in the Marcus Patent No. 1,276,552 granted August 20, 1918.

What is claimed is:

1. In combination with an electric motor and an engine cranking shaft extending therethrough, means including reduction gearing of the planetary type for drivably connecting said motor and shaft, said gearing including a planet carrier having a hub portion splined to said shaft, and means mounted directly upon said carrier hub for locking said carrier and motor against reverse rotation in the event of "backfire" of the engine during the cranking operation.
2. In combination with an electric motor and an engine cranking shaft extending therethrough, means including reduction gearing of the planetary type for drivably connecting said motor and shaft, said gearing including a planet carrier having a hub portion splined to said shaft, and means mounted directly upon said carrier hub for locking said carrier and motor against reverse rotation in the event of "backfire" of the engine during the cranking operation, said locking means including a stationary roller race surrounding said hub, and a plurality of elements normally 50 45 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340
